UNITED STATES PATENT OFFICE.

NATHAN S. WAKEFIELD, OF POMONA, CALIFORNIA.

FAUCET.

SPECIFICATION forming part of Letters Patent No. 595,222, dated December 7, 1897.

Application filed January 7, 1897. Serial No. 618,322. (No model.)

To all whom it may concern:

Be it known that I, NATHAN S. WAKEFIELD, a citizen of the United States, residing at Pomona, in the county of Los Angeles and State 5 of California, have invented a new and useful Faucet, of which the following is a specification.

The purpose of this invention is the provision of a simple means for securing a steady 10 and uniform flow when drawing off the liquid contents of a can, barrel, cask, or other receptacle in which the liquid is stored in bulk. The improved means is in the shape of a faucet, from which extends a vent-pipe whereby 15 air is admitted to the upper portion of the can or receptacle simultaneously with the unseating of the valve for drawing off the fluid contents of the receptacle. The faucet is constructed with especial reference to simplicity 20 and efficiency and to admit of access being readily had to the component parts for any desired purpose and also to be utilized as a bung or vent for replenishing the can or receptacle when required.

25 Other objects and advantages will appear in the course of the following description, and for a full understanding of the merits and advantages of the invention reference is to be had to the accompanying drawings and the 30 detailed description thereof.

The improvement is susceptible of various changes in the form, proportion, and the minor details of construction without departing from the principle or sacrificing any of the 35 advantages thereof, and to a full disclosure of the invention an adaptation thereof is shown in the accompanying drawings, in which—

Figure 1 is a side elevation of a faucet constructed in accordance with this invention, 40 showing it applied. Fig. 2 is a view similar to Fig. 1, showing the parts in section. Fig. 3 is a detail view showing the faucet and vent-pipe open. Fig. 4 is a section on the line X X of Fig. 3.

45 Corresponding and like parts are referred to in the following description and indicated in the several views of the drawings by the same reference-characters.

The faucet comprises a casing 1 and a valve 50 or plunger 2. The casing has an outer flange 3, by means of which it is secured to the can, cask, or other receptacle 4 in which the liquid

is to be drawn off is stored. A cap 5 closes the outer open end of the casing 1 and has screw-thread connection therewith, so as to be readily removed when required, and this cap has a boss 6 at its center, which is internally threaded to receive a stem 7, having an exterior thread matching the thread of the boss 6. The inner end of the casing has a valve-seat 8, against which the valve or plunger 2 closes, and is provided with a spout 9 for the egress of the liquid when the valve or plunger is unseated.

The valve or plunger 2 may be of cork, rubber, leather, or other material generally employed in the construction of devices of this character, and fits snugly within the casing 1, and has a peripheral groove 10, which is adapted to register with the vent-pipe 11, and 65 an opening or vent 12, whereby air is admitted to the upper portion of the cask, can, or other receptacle to prevent the formation of a vacuum and take the place of the liquid drawing off, thereby insuring a uniform and 70 steady stream. A metallic washer 13 is riveted or otherwise secured to the rear face of the valve and is centrally apertured, and the inner end of the operating-stem 7 has loose 75 connection therewith, so as to admit of the stem being turned to move the valve longitudinally without effecting a rotation thereof.

In practice the faucet is applied to the lowest portion of the can, tank, or receptacle, and the vent-pipe 11 is arranged to communicate 85 with the upper portion of the said receptacle. When it is required to draw off a quantity of the liquid, the stem 7 is operated so as to unseat the valve and is moved until the groove 10 thereof registers with the opening 12 and 90 vent-pipe 11, when the air entering the opening 12 will pass into the vent-pipe through the groove 10, thence into the upper portion of the receptacle to take the place of the liquid passing off, thereby insuring an uninterrupted flow and preventing spluttering and dribbling, as frequently happens with the ordinary faucet as generally constructed.

Having thus described the invention, what is claimed as new is—

A faucet constructed substantially in the manner set forth, comprising a casing having an inner and an outer flange at its inner end, the outer flange serving to secure the casing

to a receptacle, and the inner flange forming a valve-seat, a side spout near the inner end of the casing, and having a vent-opening and a vent-pipe in its side between its ends and 5 transversely alining, a valve fitting tightly within the casing and normally closing the side vent-pipe and vent-opening, and provided with a peripheral groove, an operating-stem having loose connection with the valve 10 and a screw-threaded connection with the cap of the casing for unseating the valve and bringing its peripheral groove in register with

the vent-opening and vent-pipe, and a cap having positive and adjustable connection with the outer end of the casing, substantially as specified. 15

In testimony that I claim the foregoing as my own I have hereto affixed my signature in the presence of two witnesses.

NATHAN S. WAKEFIELD.
